OTTO G. PFEIFFER, OF SALT LAKE CITY, UTAH, ASSIGNOR TO STANDARD DEVELOPMENT COMPANY, OF SALT LAKE CITY, UTAH, A CORPORATION OF UTAH.

WASHING-MACHINE.

980,558.

Specification of Letters Patent.

Patented Jan. 3, 1911.

Application filed October 13, 1909. Serial No. 522,448.

To all whom it may concern:

Be it known that I, Otto G. PFEIFFER, citizen of the United States, residing at Salt Lake City, in the county of Salt Lake 5 and State of Utah, have invented certain new and useful Improvements in Washing-Machines, of which the following is a specification.

My invention relates to washing machines 10 of that type in which a rotary drum is provided, said drum rotating within an outer casing, the drum being perforated so that the water contained within the casing and within the drum may have a thorough 15 contact with the clothes, so that air may be sucked into the water, the object of the invention being to provide a drum of such construction that considerable air will be sucked into the water and the clothes washed 20 quickly.

For a full understanding of the invention and the merits thereof and also to acquire a knowledge of the details of construction, reference is to be had to the following 25 description and accompanying drawings, in which:

Figure 1 is a front elevation of the machine partly in section; Fig. 2 is a transverse section on the line $x-y$ of Fig. 1.

Corresponding and like parts are referred to in the following description and indicated in all the views of the drawings by the same reference characters.

Referring to these figures, 2 designates 35 the body of the machine mounted on the legs 3, and 1 designates a motor whereby the machine is to be operated.

4 designates a frame attached to the end 40 of the machine and supporting the end of the main driving shaft 5^a, to which power is communicated by means of the belt wheel 5 driven by the motor 1, and from which power is communicated to the drum in any suitable manner.

45 6 designates a wringer driving shaft and 7 designates bevel gears transmitting power from the shaft 6 to the wringer rolls. The lower end of the shaft 6 is provided with the bevel gear 8 which meshes with a bevel gear 8^a on the main driving shaft.

A designates the drum and 14 designates the corrugated sides of the drum. This drum has the form of a reentrant polygon, and it will be seen that broadly speaking 55 the barrel of the drum is corrugated or pro-

vided with alternate inwardly and outwardly projecting ribs having angular sides. The sides of the drum are perforated, as at 16, and the interior face of the drum is provided with longitudinally extending, inwardly projecting riffles 15. The apex of each of the outwardly projecting ribs or angles of the drum is provided with a deflecting plate 13. This deflecting plate extends longitudinally of the drum from one end to 65 the other and projects laterally on each side partly over the adjacent face of the drum. These deflecting plates in conjunction with the adjacent inclined faces of the drum, form pockets wherein air and water is contained as the drum rotates, and act therefore as the drum is rotated to carry air into the water and agitate it more thoroughly than is possible with a drum not provided with deflecting plates. It will also be seen 70 that the interior corrugated face of the drum will act very positively upon the clothes to cleanse them, and that the riffles 15 will act to carry the clothes up the side of the drum and then allow them to drop 75 downward into the water in the lower portion of the drum. The ends of the drum are provided with the spiders 12 having thereon the outwardly projecting shafts upon which the drum is mounted, these shafts revolving 80 in the supporting bearing 11 attached to the ends of the body 2. One portion of the drum is formed of the removable section 17, which forms a door whereby clothes may be put into or taken out of the drum. This 85 door is hinged at one edge to the body of the drum, while the other margin of the door opening is provided with the buttons 20 or other latches, whereby the door may be held closed. The main body of the machine is covered by the top plate 19 having the downwardly projecting flanges fitting 90 inside the sides of the main body or tank, and the lower semi-cylindrical portion of the exterior casing 2 or body is provided with a 95 drainage opening 21 whereby the water may be emptied from the machine.

The particular feature of my invention resides in the peculiar form of the drum with its sides having reentrant angles, the 105 apices of the corrugations being provided with the deflecting plates 13. It will be seen that as the drum rotates within the main body of the structure the water and air will be carried up by the pockets formed by 110

these deflecting plates 13, and that the water will therefore drain down through the perforations 16 in the sides of the drum after the drum has passed above the water 5 in the tank. The deflecting plates projecting partly over the inwardly inclined sides of the drum, will also cause these sides between the ribs to carry up and detain a large amount of water and air as the drum 10 rotates and to suck air into the water, thus the clothes within the drum are thoroughly aerated. The pressure of the air will force the water into and through the fabric and the clothes will be thoroughly and quickly 15 cleaned.

It is to be understood that the drum constructed as above described, is adapted to be actuated by any suitable mechanism, and that it is preferably so operated that it will 20 have alternate reverse movements, the drum rotating in one direction for a definite period, and then being reversed in the direction of its movement.

Having thus described the invention what 25 is claimed as new is:

1. In a washing machine, a drum having the form of a reentrant polygon with a plurality of flat facets, and being provided with longitudinally extending deflecting plates 25 carried upon the apices of the angles of said polygon, said plates extending longitudinally the whole length of the drum and ex-

tending laterally on each side of said apices all of said plates being in alinement with each other, but the edges of each plate being spaced from the next adjacent plate, and ruffles extending across the inside face of the drum at the apices of the inwardly projecting angles of the polygon.

2. A drum for washing machines, having the form of a reentrant polygon in cross section, the angular sides of the polygon being continuous from one end of the drum to the other, and provided with perforated circular end plates closing the ends of the drum and projecting outward in coincidence with the apices of the angles of the drum, the apex of each angle of the drum being provided with a transversely extending imperforate deflecting plate projecting laterally partially over the angular side the said plates being in alinement with each other and the edges of adjacent deflecting plates being spaced from each other, the drum being thereby provided with a plurality of transversely extending pockets, the walls of the drum being provided with transversely extending perforations.

In testimony whereof I affix my signature in presence of two witnesses.

OTTO G. PFEIFFER. [L. s.]
